UNITED STATES PATENT OFFICE.

BURNETT MENKIN, OF NEW YORK, N. Y.

RETURN MECHANISM FOR MOVING PARTS OF MACHINERY.

1,151,211.

Specification of Letters Patent. Patented Aug. 24, 1915.

Application filed October 1, 1913, Serial No. 792,815. Renewed February 4, 1915. Serial No. 6,169.

To all whom it may concern:

Be it known that I, BURNETT MENKIN, a citizen of the United States, and resident of New York city, in the county of Bronx and State of New York, have invented certain new and useful Return Mechanism for Moving Parts of Machinery, of which the following is a specification.

My invention relates to return mechanism for moving parts of machinery, and has for its object to greatly simplify the construction of such parts so as to secure economy in cost, while at the same time to obtain a considerably greater efficiency in operation, as well as increased durability. I accomplish these objects by the construction and arrangement of parts hereinafter set forth.

In the present application I have illustrated my invention as applied to a die, and in the accompanying drawings, which form a part of this specification, and in which similar letters of reference refer to corresponding parts wherever they occur, I show so much only of a die press as is necessary to illustrate my invention, it being understood that unless otherwise indicated its parts are of the usual approved construction.

In the drawings:—Figure 1 is a front elevation of a die and parts connected therewith showing my invention. I show in full lines the parts in their normal position, and in dotted lines the positions these parts assume when the knockout has been actuated by arms, as F, F¹, or other actuating parts. Fig. 2 is a side elevation of a die with my invention applied thereto; and, Fig. 3 is a detail cross-sectional view of the die body and knockout.

Heretofore in constructing dies it has been usual to place the spring for the knockout in the inside of the die body. This has resulted in the following consequences:—First, in causing the die body to be made sufficiently large in size to receive such a spring, and to provide room sufficient for its movements; also in making the walls of the die body much thinner and weaker than they would otherwise be. Second, in the employment of a comparatively small and weak spring which was easily and quickly broken necessitating frequent renewals and replacements, and stoppage of the die press for this purpose.

One of the principal objects of my invention is to so construct the parts that the

knockout spring may be placed on the outside of the die body, thereby allowing a greatly reduced size of the die body and permitting the walls thereof to be made much thicker and stronger, and also reducing the cost of construction, the more particularly as this method obviates all necessity of interior fittings and adjustments, and permits of the use of an exceedingly long strong spring, which owing to its construction and manner of its use will be subjected to but little stress and strain and will have greatly longer life, and furthermore permit of replacements and renewals with ease and without serious loss of time.

In the drawings the letter A indicates the die body, B the knockout, and C a cutter, which may be secured to the die body by the set screws c. c¹ or by providing the die body and cutter with screw-threads and screwing them together. The die body and cutter may be of any usual or desired shape, material or construction.

The knock-out B is of the usual construction, and has a head b, and plunger b¹, and works in a runway a formed in the die body A. A bar extends through an opening in the head b, and ends in arms b¹. b² which project outwardly therefrom through slots a¹. a² formed in the sides of the die body. In large dies suitable arms (not shown) may be attached in any usual or desired manner to the head of the knockout, and be used instead of the bar as hereinbefore described.

To the outer surface of the die body A and substantially intermediate of the arms b¹. b² I attach pins D. D¹ which carry rollers d. d¹, and upon these rollers I place a long endless coiled spring E, which passes over the rollers d. d¹ and under the arms b¹. b² in such manner that as the knockout is depressed the arms b¹. b² will put a tension on the spring E, so that the latter acting on the knockout through the arms b¹. b² will cause the knock-out to return to its normal position in the die body whenever pressure is removed from the said arms b¹. b².

Upon the ram of the press or some other convenient place I arrange contact members such as the two arms F. F¹ in such manner that the arms b¹. b² will strike them on each up stroke of the press, and when this occurs the said arms will actuate the knockout to cause it to dislodge the finished work from the cutter C, the spring E bringing the knockout back to normal position as

soon as the arms b^1 , b^2 are moved out of engagement with the arms F, F¹.

While I have described my invention more particularly with regard to knockouts for dies, it should be understood that I do not limit myself to such a use of my invention, which will be found equally advantageous for use in other constructions of a similar character where one member is to be moved and then brought back into normal position with relation to another number.

What I claim as new and desire to secure by Letters Patent is:—

1. An outer body member, an inner movable member working longitudinally with relation thereto, and an endless coiled spring encircling said outer body member and acting upon said inner movable member to retract the same whenever it has been moved out of its normal position.
2. An outer body member, an inner movable member working longitudinally with relation thereto, and an endless coiled spring encircling said members and arranged to retract said inner movable member whenever it has been moved out of its normal position.
3. An outer body member, holding means thereon, an inner member movable longitudinally with respect to said body member, and an endless coiled spring embracing said members and engaging said holding means, and adapted to retract said movable member.
4. An outer body member, holding means thereon, an inner longitudinally movable member having actuating parts, and an endless coiled spring engaging said holding means and parts, and adapted to retract said movable member.
5. An outer body member, an inner longitudinally movable member having actuating parts thereon, holding means on said body member placed intermediate of said parts, and a coiled spring embracing said members and engaging said holding means and parts, and adapted to retract said movable member when the same has been moved.
6. An outer body member having an internal bearing, an inner longitudinally movable member working in said bearing and having actuating parts, and an endless coiled spring embracing said parts and members and acting upon said parts to retract said movable member.
7. A body member, a movable member

working in said body member provided with actuating parts, holding members provided with rollers upon said body member, and an endless coiled spring engaging said holding members and actuating parts, for retracting said movable member.

8. A body member, a movable member working in said body member provided with actuating parts, holding members provided with rollers placed intermediate of said parts upon said body member, and an endless coiled spring engaging said holding members and parts for retracting said movable member.

9. An outer body member having an internal bearing, an inner longitudinally movable member having a head provided with actuating arms working in said bearing, and an endless coiled spring embracing said members and acting upon said arms to retract said movable member.

10. An outer body member provided with elongated openings, an inner movable member provided with parts which pass through said openings to the outside of said body member, and an endless coiled spring arranged on said body member and engaging said parts to retract said inner member.

11. A slotted outer member, a movable inner member having arms which project through the slots of the outer member, holding means arranged on said outer member, and an endless coiled spring carried by said holding means and engaging said arms to retract said inner member.

12. A slotted member, a movable inner member therein having arms which project through the slots of the outer member, holding means arranged on said outer member, and a coiled spring supported by said holding means on the periphery of said outer member and engaging said arms to retract said movable member.

13. An outer member having slots, an inner member having parts projecting through said slots, and an endless coiled spring arranged around the periphery of said outer member and acting upon said parts.

Signed at New York in the county of Bronx and State of New York this 13th day of September A. D. 1913.

BURNETT MENKIN.
